(57) CLAIM

The ornamental design for a head wrap, as shown and described.

DESCRIPTION

FIG. 1 is a top front perspective view of a head wrap of a head wrap in use;

FIG. 2 is a left side view of the head wrap of FIG. 1;

FIG. 3 is a right side view of the head wrap of FIG. 1;

FIG. 4 is a rear view of the head wrap of FIG. 1;

FIG. 5 is a front view of the head wrap of FIG. 1;

FIG. 6 is a top view of the head wrap of FIG. 1; and,

FIG. 7 is a bottom view of the head wrap of FIG. 1.

The broken lines are shown for the purpose of illustrating environment and parts of the article that form no part of the claimed design.

1 Claim, 5 Drawing Sheets
